SHOE PRESS LAST

Guy O. Baker, Friend, Nebr.

Application August 29, 1934, Serial No. 741,943

15 Claims. (Cl. 12—124)

This invention relates to improvements in apparatus used in attaching half soles to the lasted uppers of boots and shoes, and particularly to that class of apparatus such as is used for cementing the half sole to the lasted uppers.

In this method of attaching half soles to the lasted uppers of shoes it is essential that the lasted upper and the inner surface of the half sole be roughened, after which the cement is applied and allowed to partially dry, after which a solvent is applied to both of the coated surfaces so as to place the cement in a plastic and sticky condition so that the parts will adhere more firmly.

In applying the half sole to the lasted upper by this method numerous difficulties arise, one of which lies in the fact that the sole is liable to slip or skid at the time pressure is being applied to the sole and while the drying process takes place. The best results are obtained when the pressure is sustained for a considerable length of time, usually in the neighborhood of twenty minutes.

Another difficulty lies in the fact that the solvent used and also the cement dries very quickly, and that it is necessary that the half sole be quickly and accurately placed in position on the lasted upper and that the half sole be firmly held in said position at the time pressure is being applied.

Another difficulty lies in the fact that the last should fit the shoe accurately so that the pressure may be applied uniformly around the edges of the last so as to avoid high and low spots in the finished sole. For this reason it has heretofore been necessary for the workman to carry a very large number of various sized and shaped lasts. Considerable time is also required on the part of the workman to select the proper last. It is, therefore, one of the objects of my invention to provide in an apparatus of the class above described an adjustable last which may be easily and quickly adjusted to fit various sizes and shapes of shoes.

A further object of my invention is to provide in a shoe press adapted to cement shoe half soles to the lasted uppers of shoes and boots improved means for gripping and holding the sole while pressure is being applied to the sole.

A further object of my invention is to provide in a shoe press of the type above described an improved pressure applying means whereby pressure may be uniformly applied around the entire edge of the sole and also to the instep portion of the sole, and to provide in connec-

tion therewith means whereby pressure may be applied to the toe and ball portion of the sole independently of pressure as applied to the instep portion of the sole, wherein the pressure may be quite uniformly distributed over the entire surface being cemented.

A further object is to provide in a shoe press having means whereby the last may be supported in an inverted position and in connection therewith an improved pressure applying means which is so mounted that it may be swung from a position adjacent to the front end of the last and moved to an operative position over the last, and in connection therewith improved means for applying pressure to a sole supported on the lasted upper of the shoe carried by the last.

A further object is to provide an improved shoe last formed preferably of two longitudinal sections, each of the said sections being adapted to be moved toward and from each other for increasing or decreasing the width of the last, and each of said sections so constructed that it may be lengthened or shortened, and in connection therewith improved means for mounting the sections of the last wherein they will pivot about vertical axes to adapt the sections to fit shoes having either pointed or blunt toes.

A further object is to provide in connection with a last of the type above described means for supporting the instep portion of the sole, and in connection therewith means for adjusting the angle of the said instep support.

My invention consists in the construction, arrangement and combination of the various parts of the device, whereby the objects contemplated are attained, as hereinafter more fully set forth, pointed out in my claims, and illustrated in the accompanying drawings, in which:

Figure 1 is a side elevation of my improved shoe press showing the pressure member moved to an operative position showing by dotted lines the manner in which the shoe is supported on the last, and in solid lines means for guiding and supporting the sole.

Figure 2 is a top view of Figure 1 with the sole support and guide removed.

Figure 3 is a sectional view taken on the line 3—3 of Figure 2, with the pressure member moved to operative position.

Figure 4 is a top view of Figure 3.

Figure 5 is a detail sectional view taken on the line 5—5 of Figure 3.

Figure 6 is a perspective view of the sole guide and support.

Figure 7 is a perspective view of one of the last

sections, said section having its cover plate removed and a portion of the last section being shown in section, with the toe member removed.

Figure 8 is a perspective view of the toe member with its cover plate removed.

Figure 9 is a perspective view of said cover plate.

Figure 10 is a detail sectional view taken on the line 10—10 of Figure 7.

10 Figure 11 is a detail sectional view taken on the line 11—11 of Figure 4.

Figure 12 is an outside perspective view of one of the last sections.

In the drawings I have used the reference numeral 10 to indicate a supporting base which is formed preferably of cast metal having a vertical guideway 11 and a notched portion 12. The guideway 11 is provided with a vertically movable slide bar 13. The forward edge of the slide bar 20 has a series of ratchet teeth 14, designed to be engaged by a pawl 15 mounted in a suitable recess 16 in the forward edge of the support 10. The pawl 15 is fixed to a rock shaft 17 by means of a set screw 18, said rock shaft having one end 25 bent rearwardly to form a handle portion 19. The back edge of the bar 13 is machined and designed to slidably support a rack bar 20, the upper end of which is designed to engage a shoulder 21 carried by the upper end of the bar 13, when the said rack bar is at its upper 30 limit of movement, said rack bar also being slidably mounted in the guideway 11, and designed to engage and be operated by a pinion 22 fixed to a shaft 23 rotatably mounted in the support 10.

35 One end of the shaft 23 is provided with a handle portion 24, by means of which the shaft 23 may be rocked. If the handle 24 is moved in a clockwise direction, as illustrated in Figure 3, then the rack bar 20 will be elevated until its 40 upper end engages the stop 21, at which time the bar 13 will be elevated and the pawl 15 will lock the said bar in said elevated position and against downward movement. If the handle 24 is then moved in a counter-clockwise direction 45 the bar 20 will be lowered relative to the bar 13 without moving the said bar 13, for the purpose hereinafter made clear.

The upper end of the bar 13 is provided with a head 25 having a lug 26 at its central portion, and 50 extending upwardly. The front end of the head 25 is also provided with a socket member 27 and openings 28. Rotatively mounted in each of the openings 28 is a last supporting arm 29 having an upwardly extending portion 30. Carried by 55 each of the members 30 is a last section 31, each of said sections representing half of the last as divided vertically and longitudinally. Each of said sections is pivotally mounted on the arm 29 so that the said sections may be set at various 60 inclines, one relative to the other, to fit various shaped shoes, while each of the arms 29 is pivotally mounted in the head 25 to permit the sections to be moved toward and from each other. The body portion 32 of each of the said sections is provided with an opening 33 (see Figure 7), 65 said openings being designed to receive the ends of a coil spring 34, as illustrated in Figure 2. This spring provides means whereby the sections will be yieldably separated.

70 For limiting the outward movement of the sections I have provided a flat spring 35, having its ends overlapping and its central portion formed with a loop 36, the ends of the spring 35 being fixed to the inner faces of the sections 31. The 75 said spring 35 thus tends to limit the outward

movement of the sections, at the same time assisting in preventing longitudinal movement of one section relative to the other, although this longitudinal movement is partially limited by the arms 29. The spring 35 is capable of being flattened so that the said sections may be moved very close together to fit comparatively narrow shoes.

It is also very desirable that the length of the last be adjusted as well as its width. The adjustment of the length of the last is accomplished by forming a rabbet 37 in the upper surface of the body member 32, so that an elevated portion 38 will be formed at the rear end of the last, which I shall term the ball portion of the last. The outer edge of the top surface of the body is curved at 39 to form a pointed end 40. The surface 37 is provided with a groove 41, in which is mounted a spring 42, the forward end of which is fixed in the groove by means of a pin 43.

The back end of the ball portion 38 is formed somewhat conical, as illustrated in Figure 10, the forward edge of the conical surface being in line with the top edge of the toe member hereinafter described, so that the entire upper surface of the last section will incline downwardly and outwardly. The body 32 is provided with an annular groove 44, having a common center with the center of the conical surface above described, the inner edge of said groove forming a part of said conical surface and designated by the numeral 45. (See Figure 10).

The said groove 44 is provided with a curved latch bar 46 designed to fit said groove and supported by a plate 46a pivoted to the member 32 by means of a screw 46b. The outer end of the member 46 terminates in a rearwardly extending member 47 that I shall term as the shank support, the upper surface of the member 47 being preferably covered with a somewhat flexible material 48, such as leather. The said member 48 engages the conical surface in a tangent manner so that the upper surface of the member 45 will terminate in the conical surface as the tangent of a curve.

The outer edge of the member 46 is provided with a series of notches 49 designed to receive a spring actuated pawl 50 for locking the member 46 in various adjusted positions.

A spring 51 is provided between the inner end of the member 46 and the upper end of the groove 44 to provide means for moving the free end of the member 47 upwardly when the pawl 50 disengages the notches 49, the pawl 50 having a rearwardly and downwardly extending handle portion 52, by means of which the pawl may be easily released.

Slidably mounted in the rabbet 37 is what I shall term a toe plate 53, having the same general outline as the upper surface of the toe portion of the body 32, said plate having a groove 54 for receiving a screw 55, by means of which the said plate is slidably supported in the rabbet.

A groove 56 is also provided for receiving a screw 57 in the toe end of the member 32. This also serves as a guide to said plate. The plate 53 is provided with a downwardly extending lug 57a designed to be hooked to the rear end of the spring 43 so that the said spring 43 will serve to yieldingly maintain the plate 53 at its forward limit of movement, the inner edge of the plate 53 being provided with a downwardly extending wing 58 designed to rest against the inner face of 75

the member 32 and within the notched or rabbeted portion 59.

The wing 58 is provided with a slot 60 for receiving a screw 61 which also assists in holding 5 the plate 54 in proper alinement with the body member.

The rear end of the plate 53 is provided with a flexible member 62 designed to slide in an arcuate slot 63 formed in the body member 32 and terminating near the central portion of the conical surface of the ball portion 38, the slot 63 also being inclined substantially parallel with the conical surface, as illustrated in Figure 10, the slot 63 beginning in the forward end of the ball portion 15 38 and tangentially of the surface 37.

By this arrangement it will be seen that the forward end of the ball portion 38 terminates in a taper, the upper surface of the ball portion 38 also always being tangent with the upper surface 20 of the member 62, regardless of the longitudinal position of the plate 53.

By this arrangement it will also be seen that the spring 42 will maintain the plate 53 at its forward limit of movement, with the rear end 25 of the member 62 just entering the slot 63.

It will also be seen that if rearward pressure is applied to the pointed end of the member 53 it will move rearwardly and cause the entire upper surface of the last to be shortened, the member 30 62 being telescopically received within the slot 63. This member 62 is preferably formed of leather which may be secured to the plate 53 by suitable rivets or other fastening means.

A cover plate 64 is provided for the plate 53 to 35 cover the slots 54 and 56, said cover plate being secured in position by suitable rivets 65, the upper surface of the cover plate being even with the upper surface of the member 62, as clearly shown in Figure 1.

40 The lower edge of the wing 58 serves to engage the toe portion of the shoe and to support the shoe in the proper shape at the time the half sole is being applied to the lasted upper.

In the construction above described it will readily be seen that the upper surface of the last, together with the upper surface of the shank support, forms a continuous and comparatively smooth surface, regardless of whether or not the toe portion is in its extended position or in its 50 inner position of movement, and regardless of the inclination of the member 47. This provides a substantial support for the shoe while being half soled.

55 In applying the shoe to the last the last sections are grasped by one hand of the operator and squeezed inwardly toward each other, after which the shoe is placed in position. The sections are then released, the spring 34 serving to expand them to fit the width of the shoe, while the 60 springs 42 tend to move the toe members forwardly and thus automatically adjust the length of the last. The free end of the member 47 is moved downwardly to its lower limit of movement before the shoe is applied. The free end of the handle bar 52 is then actuated, causing the 65 pawl 50 to release the notches 49, after which the members 47 automatically adjust themselves to the inner surface of the shank portion of the shoe.

70 For applying pressure to a half sole after it has been applied to the lasted upper, I have provided the following mechanism:

Pivotedly mounted on each end of the shaft 23, I have provided a frame member 66 having 75 divergent arms 67, the ends of which are each

provided with a slot 68. Supported between each set of arms 67, I have provided what I shall term a pressure applying frame 69, having inwardly extending lugs 70 for receiving pins 71 entering the slot 68, the said frame 69 being yieldably supported at its inner position of movement by means of springs 72 and 73, the spring 73 being somewhat larger than the spring 72. The rear end of the frame 69 is pivotally connected to a frame member 74 by means of pivots 75. Both of the frame members 69 and 74 are covered with a layer of flexible material 76, such as leather, the side edges of the member 76 being secured to the side members of the said frames by means of rivets 77, while the ends of the member 76 are unsupported. The member 76 is provided with notches 78 opposite the pivot members 75, so that the hinged portion of the member 76 is more flexible than it would otherwise be.

The under surface of the back end of the flexible member 76 is provided with a second layer of flexible material 79, the inner edges of the member 79 being tapered at 80, so that the under surface of the member 76 covering the frame member 74 is curved to better fit the ball portion 20 of the sole as pressure is applied.

A bracket 81 is pivotally connected to the free end of each of the side members of the frame 74, each of the said brackets having a laterally extended portion 82 provided with a suitable 30 opening through which a rod 83 is slidably mounted, the inner end of the rod 83 being pivotally connected to a rock arm 84 carried by the shaft 23, the outer end of the rod 83 being screw threaded and provided with thumb 35 nut 85 designed to engage the outer end of a spring 86 having its inner end resting on the member 82.

By this arrangement it will be seen that the frame members 69 and 74 may be swung from 40 the position illustrated in Figure 1 to the position illustrated in Figure 3, about the shaft 23, with a portion of the member 76 above the sole, while the back end of the member 76 rests above the shank of the shoe. The bar 13 being at its 45 lower limit of movement when the pressure applying means is swung into operative position, there is a considerable amount of clearance between the shoe and the pressure member 76.

For supporting the half sole in position in proper alinement with the lasted upper of the shoe I have provided a plate 87, the lower end of which is detachably supported in the socket 27. The upper end of the member 87 is pivotally connected to one end of a bar 88, having nail 55 receiving openings 89. The side edges of the bar 88 are provided with a number of laterally and forwardly extending members 90 formed of spring wire, having their extreme ends provided with downwardly extending portions 91 for engaging the side edges of the half sole 93, as shown in dotted lines in Figure 6.

In operation, after the shoe has been placed on the last in the manner illustrated in dotted lines in Figure 1 and in the manner before described, the half sole is then cut and shaped to fit the lasted upper of the shoe, a portion of the half sole also being shaped to fit the shank of the shoe. The member 88 is then placed in position on top of the half sole and the spring 70 wires 90 clamped in position. The sole may be further secured to the member 88 by short nails driven into the sole through the opening 89, if so desired, said nails being removed at the time the bar 88 is detached from the sole. The free 75

end of the member 88 may then be elevated and swung forwardly, after which the inner surface of the half sole may be treated with a layer of cement, and also the upper surface of the lasted upper of the shoe and the shank portion. The cement is then allowed to dry a short time, after which said surfaces are then treated with a solvent to produce a sticky condition. The member 88 is then lowered into position and into exact alinement with the lasted upper as previously placed. The frame member 69 is then elevated to position above the member 88 and the shoe. The operator then grasps the lever 24 and rotates it in a clockwise direction, as illustrated in Figure 3, causing the bar 13 to be elevated until the upper surface of the member 88 and the half sole engage the under surface of the forward end of the member 76. Further movement of the lever is then continued causing pressure to be applied to the member 76 against the action of the springs 72 and 73. After the desired pressure has been obtained the bar 13 is locked in its upper position by the pawl 15. The arm 24 is then rotated in a counter clockwise direction, causing the rock arms 84 to be rotated in a counter clockwise direction and tension to be applied to the rods 33, which in turn will cause tension to be applied to the free end of the frame 74 and the rear end of the member 76, causing the rear end of the half sole to be folded down snugly around the outer surface of the shank portion of the shoe sole. The frame member is locked in this position by means of a pawl 92 designed to engage the teeth of the pinion 22. The press may then be allowed to stand for the desired time until the cement sets, after which the latch 92 may be released and also the pawl 15 by means of the lever 19. This will then permit the bar 13 to be lowered and pressure released from the member 76.

Considerable advantage is gained in providing the open frame members 69 and 74, together with the flexible strip 76, said strip 76 being supported at each of its side edges with the strip lying transversely across the top of the half sole. By this arrangement it will be seen that the greatest tension is applied along the side edges of the last where the cement is applied, no cement being usually applied to the central portion of the half sole.

By providing the notches 78 in the flexible member 76 the side edges of the back end of the member 76 will more readily fold over the side edges of the shank portion of the sole as pressure is being applied.

Referring to Figure 12 it will be seen that the back end of the flexible member 62 projects outwardly of the outer surface of the body member 32, the back end of the member 62 being substantially the same width as its forward end.

By this arrangement the full width of the central portion of the last may be provided when the toe member is at its forward position of movement, as illustrated in the dotted lines in Figure 12. This outwardly extending end does not hinder in applying pressure to the outer edge of the sole, inasmuch as said outwardly extending portion engages the side of the shoe at a point a considerable distance from the sole.

Thus, it will be seen that I have provided a shoe press which is of comparatively simple and inexpensive construction and rigidly built so as to stand a large amount of wear without get-

ting out of order, and so constructed that a large amount of time is saved in eliminating the necessity of having to find a new last each time a shoe is placed in position for repair.

Furthermore, the shoe is placed in an inverted 5 position so that the half sole being applied is clearly visible and may be quickly and easily alined with the lasted upper.

Means is also provided whereby the half sole will be rigidly held in position while pressure is 10 being applied, to avoid skidding of the half sole relative to the shoe.

It will further be seen that pressure is applied to the side edges of the flexible pressure member at substantially six points. Each of the tension 15 devices is yieldable so that the half sole will fit any slight variation in the surface of the shoe. This provides means whereby a comparatively uniform pressure may also be applied to the half sole, the spring 73 being made larger than the 20 spring 72 simply because the back portion of the half sole is of larger area than the area of the forward portion of the sole.

I claim as my invention:

1. In a device of the class described, a last comprising longitudinal sections, each of said sections being adjustable as to length; means for supporting each section to swing about a vertical pivot; means for pivotally supporting each of said pivots whereby the sections of said last may be 30 moved toward and from each other; yieldable means supported between the sections of said last to maintain them in their separated positions; and means for limiting the outward movement of 35 said sections.

2. In a device of the class described, a last comprising longitudinal sections, each of said sections being adjustable as to length; a shank support pivotally connected to the back end of each of said sections; means for supporting each section to swing about a vertical pivot; means for pivotally supporting each of said pivots whereby the sections may be moved toward and from each other; and yieldable means supported between the sections to maintain them in their separated 45 positions.

3. A shoe last comprising separated longitudinal sections, each of said sections being adjustable as to length; a shank support pivotally connected to the back end of each of said sections; means for adjusting the angle of said shank support relative to the upper face of said last; means for supporting the sections of said last to move toward and from each other; means for yieldably supporting said sections in separated 50 positions; and means for pivotally connecting each of said sections to its supporting means to swing about a vertical axis.

4. In a device of the class described, a last comprising longitudinal sections, each of said 60 sections being adjustable as to length; means for supporting each section to swing about a vertical pivot; means for pivotally supporting each of said pivots whereby the sections of said last may be moved toward and from each other; and yieldable 65 means supported between the sections of said last to maintain them in their separated positions.

5. In a shoe last, a body member comprising right and left sections, each section comprising a body member having a rabbeted surface, the back 70 end of said body having a ball portion terminating in a somewhat conical surface, said body having an arcuate slot the outer end of which terminates in the forward edge of said ball portion and tangentially of the rabbeted surface; a 75

- 5 toe member slidably mounted on the rabbeted surface to move toward and from the ball portion, the rear end of said toe member terminating in a flexible portion slidably mounted in said arcuate slot; a rearwardly extending shank support pivoted to said body to swing around the center of said conical surface; means for locking the shank support at various inclined positions; means movably supporting said sections to permit them to move toward and from each other; yieldable means tending to separate said sections; and yieldable means tending to move said toe members away from the ball portions.
- 10 6. In a shoe last, a body member comprising right and left sections, each section comprising a body member having a rabbeted surface, the back end of said body having a ball portion terminating in a somewhat conical surface, said body having an arcuate slot the outer end of which terminates in the forward edge of said ball portion and tangentially of the rabbeted surface; a toe member slidably mounted on the rabbeted surface to move toward and from the ball portion, the rear end of said toe member terminating in a flexible portion slidably mounted in said arcuate slot; a rearwardly extending shank support pivoted to said body to swing around the center of said conical surface, the inner end of the support terminating tangentially of said conical surface; means for locking the shank support at various inclined positions; means movably supporting said sections to permit them to move toward and from each other; means pivoting said sections to said supporting means to swing about vertical axes; yieldable means tending to separate said sections; and yieldable means tending to move said toe members away from their respective ball portions.
- 15 7. In a shoe last, a body member comprising right and left sections, each section comprising a body member having a rabbeted surface, the back end of said body having a ball portion, said body having an arcuate slot the upper end of which terminates in the forward edge of said ball portion and tangentially of the rabbeted surface; a toe member slidably mounted on the rabbeted surface to move toward and from the ball portion, the rear end of said toe member terminating in a flexible portion slidably mounted in said arcuate slot; means movably supporting said sections to permit them to move toward and from each other; yieldable means tending to separate said sections; and yieldable means tending to move said toe members away from their respective ball portions.
- 20 8. A last comprising, in combination, longitudinal sections, each section including toe and ball portions, each section being adjustable as to length between its ball and toe portions; means for supporting said sections to move toward and from each other; and a shank support adjoining each ball portion.
- 25 9. A last comprising, in combination, longitudinal sections, each section including toe and ball portions, each section being adjustable as to length between its ball and toe portions; means for supporting said sections to move toward and from each other; a shank support adjustably connected to each ball portion; and means for locking said shank support in various adjusted positions.
- 30 10. In a device of the class described, a last comprising longitudinal sections, each of said sections being adjustable as to length; means for supporting each section to swing about a vertical pivot; and means for pivotally supporting each of said pivots whereby the sections of said last may be moved toward and from each other.
- 35 11. A shoe last comprising, in combination, right and left sections, each section including a ball portion at its back end, each section having an arcuate slot the upper end of which terminates in the forward edge of said ball portion and tangentially of the upper surface of said section; a toe member slidably mounted on the upper surface of said section to move toward and from the ball portion, the rear end of said toe portion terminating in a flexible portion slidably mounted in said arcuate slot; and means movably supporting said sections to permit them to move toward and from each other.
- 40 12. A shoe last comprising, in combination, right and left sections, each section including ball and toe portions, the ball portion having an upwardly and forwardly inclined slot terminating in the forward edge of said ball portion, the toe portion being mounted to move toward and from the ball portion and having its back edge provided with a flexible member slidably mounted in said slot whereby the areas of the upper surfaces of the sections may be increased or decreased by moving the toe portions thereon toward the ball portion, or vice versa; and means for mounting said sections to move toward and from each other.
- 45 13. A shoe last comprising in combination a section including a ball and toe portion, the ball portion having an upwardly and forwardly inclined slot terminating in the forward edge of said ball portion, the toe portion being mounted to move forwardly and from the ball portion, and having its back edge provided with a flexible member slidably mounted in said slot whereby the area of the upper surface of said section may be increased or decreased by moving the toe portion thereon towards the ball portion, or vice versa.
- 50 14. A shoe last comprising in combination a section including a ball and toe portion, the ball portion having an upwardly and forwardly inclined slot terminating in the forward edge of said ball portion, the toe portion being mounted to move forwardly and from the ball portion, and having its back edge provided with a flexible member slidably mounted in said slot whereby the area of the upper surface of said section may be increased or decreased by moving the toe portion thereon towards the ball portion or vice versa; a shank support adjustably connected to each ball portion; and means for locking said shank support in various adjusted positions.
- 55 15. In a device of the class described, a last comprising longitudinal sections, each of said sections being adjustable as to length; means for supporting said sections to move toward and from each other; yieldable means for normally maintaining said sections elongated; and means for yieldably maintaining the sections in normal separated positions whereby the last will be automatically adjusted as to length and width to fit the shoe as the shoe is placed in position therein.
